UNITED STATES PATENT OFFICE.

GOTTFRIED E. SCHWEIZER, OF BRIDGEPORT, CONNECTICUT.

HEAD-LAMP FOR AUTOMOBILES.

1,235,065.

Specification of Letters Patent. Patented July 31, 1917.

Application filed January 25, 1917. Serial No. 144,440.

To all whom it may concern:

Be it known that I, GOTTFRIED E. SCHWEIZER, a citizen of the United States, residing at the city of Bridgeport, county 5 of Fairfield, State of Connecticut, have invented certain new and useful Improvements in Head-Lamps for Automobiles; and I do declare the following to be a full, clear, and exact description of the invention, such 10 as will enable others skilled in the art to which it appertains to make and use the same.

This invention relates to certain new and useful improvements in a head lamp for 15 automobiles and has for an object to improve the construction whereby the direct rays may be intercepted by an adjustable screen and thereby avoid a dazzling light being shown in the eyes of those approaching.

Another object is to provide laterally disposed red and green lights on the screen 20 so as to guide a person approaching in passing on the green light side and avoiding the danger side.

The invention further resides in the features of construction, and the arrangements and combinations of parts hereinafter described and claimed, reference being had to the accompanying drawing wherein—

Figure 1 is a horizontal section through 25 a head lamp illustrating the present invention in top plan;

Fig. 2 is a front elevation of the present invention as embodied in a head lamp;

Fig. 3 is a vertical section thereof;

Fig. 4 illustrates the invention as applied to head lamps when two are employed on the front of a vehicle, and,

Fig. 5 is a horizontal section through a 40 lamp illustrating a further modification.

Referring particularly to Figs. 1, 2 and 45 3, the preferred form of the invention is depicted as comprising an inner, fixed hemispherical screen 1, which is provided with a sleeve part 2, and a movable, outer hemispherical screen 3 that is pivoted to the fixed screen at substantially diametrically opposite points, as indicated at 4.

The inner screen or screen section 1 has 50 its sleeve part 2 mounted on the lamp socket 5 for supporting the screen section above the lamp 6, said section further being cut away, as at 7, in its forward edge portion through which the light rays may pass in diverging 55 lateral courses.

The outer screen section 3 is provided with lateral openings 8 in the left one of which is inserted a green glass and in the right one a red glass, said openings being registerable with the cut away portions or 60 recesses 7 to permit of the light rays being projected through the glasses at a higher angle, as viewed in Fig. 3.

The outer screen is adjusted on the inner screen so as to intercept the direct rays of 65 light that would otherwise pass upwardly with a dazzling effect on those approaching, and permit the rays to shine from the bottom onto the road. The movable outer screen is retained at the desired adjustment 70 by set screw 9 that impinges against the fixed screen.

Thus, upon proper adjustment of the outer screen, the direct light rays will be screened 75 so as not to dazzle the eyes of those approaching. The lateral red and green lights further aid an approaching person by directing him to pass the vehicle on the left and avoid the red or danger side.

In case there is only one head light on an 80 automobile, the red and green side lights would be provided as just described, so that the red light would always show on the right hand side of the automobile and the green light on the left side, this being in ac- 85 cordance with the usual traffic rules which require an approaching vehicle to pass to the right and an overtaking vehicle to pass to the left.

Where two head lamps are employed it is 90 necessary to have only one lateral opening in the outer section of each screen, such opening being disposed toward the adjacent side of the vehicle so as to direct the rays outwardly, as shown at 10 in Fig. 4. In this 95 instance the left light or glass will be green and the right light red, as is obvious.

In the modification depicted in Fig. 5, both screen sections are pivotally supported between the forks of a bracket 11, the latter 100 having a sleeve part 12 which slips over the lamp socket 5. The inner screen 13 has its rear edge concaved to closely fit the base of the lamp whereas the outer section 14 carries the set screw 15 for securing the screens 105 relatively fixed.

In either form it is obvious that the lamp may be completely enveloped by the screens so as to shut out all light whatsoever, or said screens may be adjusted to provide a 110

small or large volume of light as conditions require.

The outturned lip 16 provides a light-tight joint between the sections as well as determines the movement of the outer screen on the inner one by the screw 9 engaging therewith.

The parts are simply constructed and arranged and the screen, as a whole, not only 10 sheds the bright rays but also affords a means of guide, to those approaching, by the embodiment of the red and green lights.

What is claimed is:

1. A screen for head lamps comprising, in 15 combination with a lamp socket, an inner hemispherical screen section having its forward edge provided with lateral recesses, an outer hemispherical screen section pivoted to the first screen section and provided with 20 red and green lights registerable with the recesses thereof, and means for mounting the screen sections.

2. In a screen for head lamps, an inner hemispherical screen section, an outer hemi- 25 spherical screen section pivoted thereto, laterally disposed green and red lights provided

in the outer section, and means for mounting the sections.

3. In a screen for head lamps, an inner hemispherical screen section, an outer hemi- 30 spherical screen section pivoted thereto, laterally disposed green and red lights provided in the outer section, and means for mounting the sections including a sleeve support.

4. In a screen for head lamps, an inner screen section, an outer screen section, a sleeve support having a forked bracket part, and means pivotally connecting the screen 35 sections to the forked bracket part.

5. A screening device for head lamps, comprising a pair of pivoted screen sections of spherical curvature, a light aperture in each of the sections laterally disposed on opposite sides respectively, and means for 40 45 mounting the screens.

In testimony whereof I affix my signature in presence of two witnesses.

GOTTFRIED E. SCHWEIZER.

Witnesses:

T. W. GRUILTOP,
M. T. LONGDEN.
